UNITED STATES PATENT OFFICE.

GEORGE R. HORTON, OF SAN DIEGO, CALIFORNIA, ASSIGNOR OF ONE-HALF TO EDGAR L. NICHOLSON, OF SEATTLE, WASHINGTON.

ENDLESS PROPELLER FOR BOATS.

No. 813,648.

Specification of Letters Patent

Patented Feb. 27, 1908.

Application filed April 13, 1906. Serial No. 255,405.

To all whom it may concern:

Be it known that I, GEORGE R. HORTON, a citizen of the United States, residing at San Diego, in the county of San Diego and State of California, have invented certain new and useful Improvements in Endless Propellers for Boats, of which the following is a specification.

This invention consists of a novel form of endless propeller for small boats, ships, yachts, or power-driven vessels of any type.

The invention resides in the provision of an endless propeller or propellers of special construction by which the friction of mounting of the propellers upon the boat is reduced to a minimum, enabling the vessel to be driven at a maximum speed, the various detail parts comprised in the propeller structure being simplified and combined in such a manner as to admit of ready access thereto for purposes of repair or the like.

This invention involves, further, the use of a plurality of chain propellers upon a single vessel, said propellers being operated by a suitable motor, the invention including peculiar connections whereby the operation of the propellers may be controlled in propelling the ship forwardly, rearwardly, and in turning.

For a full description of the invention and the merits thereof and also to acquire a knowledge of the details of construction of the means for effecting the result reference is to be had to the following description and accompanying drawings, in which—

Figure 1 is a vertical longitudinal sectional view through the hull of a vessel, bringing out more clearly the construction of the propeller. Fig. 2 is a sectional view centrally broken away, taken about on the line X X of Fig. 1. Fig. 3 is a plan view showing the hull of the vessel, bringing out the arrangement of the propellers. Fig. 4 is a plan view showing a portion of a raceway upon the vessel and a portion of the endless propeller mounted in the raceway. Fig. 5 is a perspective view, parts broken away, showing more clearly the detail construction of the chains of the propeller and mounting of the paddles thereon. Fig. 6 is a perspective view of parts of the operating mechanism and connections between the same and the power-shafts. Fig. 7 is a front elevation showing the clutch members and intermeshing gears

carried by the power-shafts and the engine-shaft.

Corresponding and like parts are referred to in the following description and indicated in all the views of the drawings by the same reference characters.

In carrying out the invention the hull 1 of a vessel is illustrated, the vessel being of any type at present in use to which the invention is susceptible of application, the construction of the vessel being immaterial save with regard to the mounting of the propeller or propellers therein. The hull 1 is provided with raceways 2, upon which the endless propellers, two of which are preferably used in the construction illustrated, are adapted to travel. The raceways 2 are composed of a track or bed extending horizontally through the body of the ship between the bottom and the upper decks of the hull, as shown at 3, said raceways extending downwardly at the ends (see 3^a) and thence extending along the bottom of the vessel at 3^b. The bed or base of each raceway 2 is preferably of metal, and at opposite sides of said raceway, over which a single endless propeller travels, are located longitudinal guide-flanges 4, which guide the propeller in its movement over the raceway therefor. The propellers used upon the ship or vessel are of like construction, and the number of propellers depends upon the size of the vessel for obvious reasons.

One only of the propellers will be described, and the same consists of a plurality of chains 5, each of which is composed of a plurality of links 6. The links 6 of each chain are pivotally connected together by means of a pintle-rod 7, which passes through apertured lugs 8, formed by the extremities of each link 6 aforesaid. The pintle-rods 7 are utilized not only to connect the links 6 of each of the chains 5, but these pintle-rods 7 are designed to form a connection between the several chains 5 of each endless propeller, and for this reason these rods pass through the lugs 8 of transversely-aligned links 6 of the various chains 5. The pintle-rods 7 are of peculiar construction, having antifriction-rollers 9 mounted thereon between the several chains 5, said rollers 9 being arranged for contact with the bed or base of the raceway 2, so as to reduce friction between the propeller and its raceway to the greatest degree practicable. The extremities of the pintle-rods 7

are enlarged, as shown at 9, and the outer sides of the enlarged portions 9 are concaved to form seats, in which are located the anti-friction-balls 10. The balls 10 are mounted 5 between the heads or enlarged portions 9 of the pintle-rods 7 and the spaced flanges 4 of the raceway 2, and these balls 10 reduce the friction between the sides of the endless propeller and the raceway in which it is mounted 10 to a minimum also. The pintle-rods thus co-operate with the flanges 4 to a certain extent 15 in guiding the propeller in its longitudinal movement upon the raceway 2; but in addition to the pintle-rods it is designed to utilize other guide means in the form of guide members 11, which are projected laterally from 20 the outer side of each of the links of the outer chain 5 at opposite sides of the propeller.

The guide members 11 are of approximately U form and receive between the sides thereof the upper portions of the guide-flanges 4. The members 11 thus have an interlocking connection with the flanges 4 and effectively obviate lateral play of the endless 25 propeller as it travels upon its raceway, causing the propeller to move smoothly and without noise. Between the sides of each U-shaped guide member 11 is mounted a roller 12, arranged to travel upon the flange 4 adjacent, reducing friction between the members 11 and said flanges in an obvious manner. The members 11 virtually form spaced ears projecting from the outer side of the links 6 of the outer chains 5.

It will be understood that the number of 30 chains 5 used for each endless propeller may be varied according to the size of the vessel and other existing conditions, and to further reduce the friction between the chains 5 of 40 the propeller and the raceway in which it moves the various links 6 of the chains 5 are provided at a point about intermediate their ends with bars 13, connecting opposite sides of each link. Rollers 14 are mounted upon 45 the bars 13, and said rollers are adapted to come into direct contact with the raceway 2 to assist the rollers 8 in reducing the friction.

The chains 5 pass about sprocket-wheels 15 and 16 at opposite ends of the raceway 2 for 50 each propeller. The sprocket-wheels 15 are mounted upon a shaft 17, and the said wheels 15 coat with the sprocket-chains 5 in the usual manner, the rollers 14 reducing friction between the chains 5 and the sprocket-wheels 55 15 and 16 in a manner readily apparent. The wheels 16 are carried by a power-shaft 18, and the power-shaft 18 of each endless propeller projects at one end outwardly from the propeller, so as to admit of application of the 60 power at this point. The shafts 17 and 18 are of course journaled in suitable journal-boxes, and stuffing-boxes are provided therefor to prevent any water carried to the shafts 17 and 18 by the propeller from entering the 65 interior of the vessel. The power may be

applied to the shafts 17 of the propellers as well as to the shafts 18. However, for average-sized vessels the application of the power at both ends of the propeller will be unnecessary. Further, the propellers may travel 70 about sprocket-wheels near the bottom of the vessel and at the lower portion 30 of the raceway 2; but ordinarily sprocket-wheels at this point may also be dispensed with. The paddles 19 of the endless propellers are attached to the links 6 at intervals in the length of the chains 5 composing said propellers, said paddles being rigidly attached to transversely - alined links by any substantial means. Braces 20 may connect the outer 75 extremities of the outer upper portions of the paddles 19 with the adjacent link 6 of the outer chain 5, to which said paddle may be secured, and the paddles 19 will be rigidly supported by this means. The motor mechanism, which may be an engine or engines of any conventional type, is preferably mounted 80 between the propellers of the vessel and is operably connected with the shafts 18 in a peculiar manner. 85

Specifically describing the parts of the power mechanism illustrated in the drawings, the numeral 21 indicates an engine - shaft which is connected with a suitable motor and which extends preferably longitudinally of 90 the vessel, being arranged between the endless propellers. The motor to which the engine-shaft 21 is connected is not shown, this not being essential, as any class of engine may be utilized. The power - shafts 18, which 95 carry the sprocket-wheels 16 over which the chains 5 of the endless propellers pass, have the inner end portions thereof adjacent one another, as shown most clearly in Fig. 3 of the drawings. Mounted upon the adjacent 100 ends of the shafts 18 are movable and stationary clutch elements 22 and 23, respectively. The movable clutch element 22 is splined upon the shaft 18, carrying the same, and is movable toward and from the clutch 105 elements 23, so as to be engaged with and disengaged from the latter.

When the clutch elements 22 and 23 are in engagement with each other, the shafts 18 are connected for simultaneous operation, being driven in the predetermined direction by a bevel-gear 24 upon the engine-shaft 21, the gear 24 being in mesh with a similar bevel-gear 25, keyed to the power-shaft 18 opposite that having the clutch member 22. The 110 gears 24 and 25 are normally in mesh, so that when the clutch elements 22 and 23 connect the shafts 18 the engine-shaft 21 is adapted to communicate power to the shafts 115 18 to effect travel of the endless propellers in either direction, since the shaft 21 may be readily reversed in backing the vessel. Mounted upon the shaft 18, carrying the clutch element 22, is a movable bevel-gear 120 26, which also has a feather-and-spline con- 125

nection with said shaft, and this gear 26 is of a form similar to the gear 25, being adapted, however, to be thrown into and out of mesh with the engine-shaft gear 24. The gear 26 is utilized to enable the endless propellers to be reversed in order to turn the vessel. Levers may be used to impart sliding movement to the members 22 and 26 in order to respectively clutch and engage the same with the clutch elements and the gear 24. In operation when the ship is moving forwardly the gear 24 of the engine-shaft 21 is in engagement with the gear 25 of the shaft 18, and the shafts 18 are operably connected by engagement of the clutch elements 22 and 23.

In order to reverse the endless propellers, it is only necessary to reverse the engine-shaft 21 in an obvious manner. To turn the ship, however, the clutch element 22 is thrown out of clutch with the element 23, and the gear 26 is thrown into engagement with the gear 24 of the engine-shaft 21. Revolution of the gear 24 will therefore communicate reverse motion to the shafts 18, as the gear 24 is in mesh with both of the gears 25 and 26, and the ship may thus be turned without moving either forwardly or sternward.

Having thus described the invention, what is claimed as new is—

- 30 1. In combination with a vessel, a raceway, an endless propeller arranged for travel upon the raceway, said propeller embodying a plurality of chains, rollers mounted between the chains to reduce the friction between the chains and the raceway, and paddles carried by the chains aforesaid.
- 20 2. In combination with a vessel, a raceway, an endless propeller arranged to travel upon the raceway and embodying a plurality of chains, each chain including a plurality of links, rollers mounted in the links to reduce friction between the raceway and the propeller, and paddles carried by the chains aforesaid.
- 35 3. In combination with a vessel, a raceway thereon, an endless propeller arranged to travel upon the raceway, said propeller comprising a plurality of chains composed of links, pintle-rods connecting adjacent links of each chain and adjacent chains, paddles carried by the chains aforesaid, and rollers carried by individual links of the several chains.
- 45 4. In combination with a vessel, a raceway thereon, an endless propeller arranged to travel upon the raceway, flanges at opposite sides of the raceway, the propeller embody-

ing a plurality of endless chains, paddles carried by the chains, antifriction-bearings between the chains and the flanges of the raceway, and antifriction-rollers supported by the propeller between the chains thereof.

5. In combination with a vessel, a raceway thereon, an endless propeller arranged to travel upon the raceway, flanges at opposite sides of the raceway, the propeller embodying a plurality of endless chains, paddles carried by the chains, antifriction-bearings between the chains and the flanges of the raceway, and other antifriction-bearings between the chains and the bed or body of the raceway.

6. In combination with a vessel, a raceway thereon, flanges at opposite sides of the raceway, an endless propeller arranged to travel upon the raceway and composed of a plurality of chains, pintle-rods connecting adjacent links of the chains and also connecting adjacent chains, antifriction-bearings carried by the pintle-rods between adjacent chains to reduce friction between the propeller and the raceway, and other antifriction-bearings between the pintle-rods and the flanges of the raceway.

7. In combination with a vessel, a raceway thereon, an endless propeller arranged to travel upon the raceway, said propeller comprising a chain, flanges at opposite sides of the raceway, and guide members carried by the chain of the propeller and engaging over the flanges of the raceway.

8. In combination with a vessel, a raceway thereon, an endless propeller arranged to travel upon the raceway, said propeller comprising a plurality of chains, flanges at opposite sides of the raceway, and guide members projected from links of the outer chains of the propeller and engaging over the flanges of the raceway.

9. In combination with a vessel, a raceway thereon, an endless propeller arranged to travel upon the raceway, said propeller comprising a plurality of chains, flanges at opposite sides of the raceway, guide members projected from links of the outer chains of the propeller and engaging over the flanges of the raceway, and roller-bearings between the guide members and the flanges.

In testimony whereof I affix my signature in presence of two witnesses.

GEORGE R. HORTON.
